(57) **CLAIM**

The ornamental design for automobile flares, substantially as shown and described.

DESCRIPTION

FIG. 1 is a perspective view of a driver side front flare of automobile rear flares showing my new design,

FIG. 2 is a front view thereof,

FIG. 3 is a top view,

FIG. 4 is a bottom view,

FIG. 5 is a front side view,

FIG. 6 is a rear side view,

FIG. 7 is a back view shown for illustrative purposes and completeness of disclosure, but does not form a part of the ornamental design,

FIG. 8 is a perspective view of the passenger side front flare of automobile rear flares showing a second embodiment of my new design,

FIG. 9 is a front view of FIG. 8,

FIG. 10 is a top view of FIG. 8,

FIG. 11 is a front view of FIG. 8,

FIG. 12 is a front side view of FIG. 8,

FIG. 13 is a rear side view of FIG. 8; and,

FIG. 14 is a back view of FIG. 8 shown for illustrative purposes and completeness of disclosure, but does not form a part of the ornamental design.
